HOG FEEDER

Emanuel Uhrenholdt, Clearwater, Nebr.

Application June 29, 1948, Serial No. 35,870

3 Claims. (Cl. 119—54)

1

This invention relates to self feeders and is adapted to be used by hogs or other farm stock when feeding; whereby as the animals root in the feed bin, they automatically actuate the supply means to provide a continuous flow of feed, regulated never to exceed a predetermined quantity.

A primary object of the invention is to provide a feeding trough for stock that the animals, and particularly hogs, such trough being able to supply just enough feed for consumption without providing an excess which will be scattered and wasted, the self feeding being effected by rollers adapted to be rotated by the stock as they eat, such rotation serving to supply additional feed for further consumption, and when the feeding ceases, no further supply occurs.

Another object of the invention is to provide means to insure supply of feed at all times, overcoming the tendency for the weight of the feed in the storage bin to prevent supply through suitable openings, such means consisting of a number of spring steel bars in the feed bin adapted to be vibrated by rotation of the feed rollers, such vibration causing feed to be supplied to the trough.

A further object of the invention is to provide a pivoted roof whereby the roof of the bin is pivoted to either side in order to enable a supply of feed to be poured into the storage compartment, eliminating the necessity of supply doors, or dis-assembly when it is necessary to fill the feed receptacle, such pivoted roof being spring controlled whereby it is a simple matter to lift against the resistance of the spring and slide the top in either direction to expose the interior of the trough.

And a further object of the invention is to provide a feeder that is capable of being varied in length, by merely supplying additional feed rollers and agitators, as is deemed necessary.

Other objects of the invention reside in the detail of construction and the combination of the various parts and in the mode of operation, as will hereinafter appear.

The following is a detailed description of the preferred embodiment of the invention and is illustrated in the accompanying drawings, wherein—

Figure 1 is a perspective view of the feeder;

Figure 2 is a vertical sectional view and is taken substantially on line 2—2 of Figure 3;

Figure 3 is a transverse vertical view and is taken substantially on line 3—3 of Figure 2;

Figure 4 is a perspective view of the roller that permits the feed to be supplied automatically;

2

Figure 5 is a side elevation of the feeder, partly in section and illustrating the roof in open position;

Figure 6 is a top plan view of the invention, with the roof open and closing a portion of the structure therein; and

Figure 7 is a perspective view of the vibrating or agitating means.

Referring to the figures, the feeder is illustrated generally by numeral 10 and is shown as adapted to feed a total of six hogs or other stock. The feed bin 10 consists of a floor 12 and a pair of oppositely disposed sides or end walls 14. The end walls 14 terminate in an apex 16, adapted to seat securely thereon a similarly shaped roof or closure 18. The roof 18 includes actuating handle 20 so that the roof may be pivoted in either direction, as is illustrated in Figure 5, to expose the interior 22 of the storage bin.

Pivoting movement of the roof is attained by means of a link or lever 24 secured to pivot pin 26 extending through sides 14. The lever 24 is apertured at one end, as at 28, to receive one end of a suitable coil spring 30, and the remaining end of the coil spring 30 is secured to an eye bolt 32 mounted in roof 18. Thus, when handle 20 is dropped and roof 18 is pulled upward slightly to overcome the resistance of spring 30, the entire roof may be pivoted in either direction to expose the interior of the device. Suitable feed is then poured into the bin, after which roof 18 is then returned to its original position illustrated in Figure 1 for closing the bin.

Walls 34 define the side of bin 22 and taper inwardly and downwardly toward the bottom 12. It will be noted, by inspection of Figure 3, that walls 34 terminate a short distance above the bottom 12 of the feeder 10 and are spaced apart at the lower free extremity, for a purpose soon to appear.

A plurality of spacing walls or partitions 36 are provided at predetermined distances throughout the length of automatic feeder 10 to divide the device into a plurality of individual feed chambers. In the device illustrated a total of six chambers are attained. Of course, it is to be understood that the invention is not limited to this number, and may be varied to suit the requirement of the individual. The spacing walls 36 are triangular in shape, the rear edge thereof being adapted to conform to the taper of receptacle walls 34. A U-shaped apron forming member 38 is provided for each chamber in any suitable manner, and in the present instance by continuing bottom 12 in the cut-out tapering flange

illustrated in Figures 1 and 3. By so constructing the device, a trough 40 is obtained, which will receive the feed supplied from the bin 22 and will not be scattered during the feeding process, as is usually the case with feeding devices employed today.

A pair of longitudinal shafts 42 extend longitudinally of the feeder and are secured to the side walls 14. The shafts 42 are substantially stationary and the two illustrated are provided, one being for each side of the tapered walls 34. A plurality of individual rollers 44, best illustrated in Figure 4, are mounted on shafts 42 for rotation thereon. In the present embodiment, a total of six such rollers are supplied, each roller being positioned within the chamber provided by wall 36 and sides 14. The rollers 44 have secured on the outer periphery thereof teeth or button members 46, for a purpose presently to be described. The teeth are provided in spiral arrangement, as may be seen from an examination of the figures. The rollers 44 are positioned directly beneath the lower extremity of tapered walls 34 and above bottom 12 of the device. In this way, the rollers 44 operate as valves, or gate means whereby feed travelling from storage bin 10 is controlled by the operation of rollers 44.

Rods 48 extend longitudinally of the feeder 10 and one is provided for each side thereof. Welded to rods 48 are a plurality of depending bars 50 having lower ends terminating slightly below walls 34 and are in constant engagement with teeth 46 and rollers 44. The bars 50 are of flat, spring steel construction and are especially adapted to vibrate freely. Longitudinal rods 52 extend through feeder 10 below rods 48 and in parallel relation thereto, and contact the inner faces of the bars 50. The rods 52 thereby serve to limit the vibratory movement of bars 50 when they are agitated by rollers 44. While a plurality of fixed bars have been provided for each side of the feeder, the number may be varied as is needed to efficiently provide a steady supply of feed to trough 40.

In the use of the device, the rods 52 are adapted, by actuation of rollers 44 to automatically supply feed as the feed is consumed. Roof 18 is pivoted into open position, as was explained above, and bin 20 is filled. Roof 18 is then swung back into closed position and the feeding device is entirely closed against inclement weather. When an animal starts feeding, and particularly hogs, he will root under rollers 44 at a selected trough. His snout gets under teeth 46, after which upon removing his snout, the teeth are urged upwardly and rollers 44 rotate. Feed is then enabled to travel into trough 40 by this movement. At the same time steel bars 50 are actuated and vibrated by teeth 46 upon which they engage thus preventing the feed from packing and storing in the bottom of bin 22. Apron forming members 38 prevent any feed from overrunning trough 40 and being scattered or wasted thereby.

From the above description, these several objects have been obtained. Any suitable material may be employed in the construction of the device, while a preferred embodiment of the invention has been shown and described, it is to be understood that various changes in size, shape and arrangement of parts might be made without departing from the spirit of the invention and the scope of the appended claims.

Having described the invention, what is claimed as new is:

1. An automatic hog feeding device comprising a bin having a bottom wall, a pair of end walls secured to the bottom wall, a pair of downwardly and inwardly inclined side walls secured to said end walls and having lower edges spaced above said bottom wall and a closure supported by said end walls and said side walls, a pair of elongated apron forming members carried by the bottom wall and curved toward the side walls, said apron forming members being spaced above the bottom wall and having longitudinally spaced transverse slots, a plurality of spaced parallel, substantially vertical spacer walls secured to the outer surfaces of said side walls and to the bottom wall to define a plurality of troughs, said spacer walls being received in said slots, said apron-forming members having openings therein providing entrances to feed disposed on the bottom wall, means located within the bin and disposed between said side walls for agitating feed in the bin, and means mounted in said bin beneath said apron-forming members for directing feed in the bin toward the openings in said apron-forming members, said last-mentioned means actuating said agitating means.

2. The combination of claim 1 wherein said means for directing feed in the bin toward the openings in said apron-forming members includes a pair of longitudinally extending shafts carried by the end walls and the spacer walls, said shafts being spaced between the lower edges of the side walls and the bottom wall, and a plurality of toothed members rotatably mounted on the shafts and spaced from each other by said spacer walls.

3. The combination of claim 1 wherein said means for agitating feed in said bin includes a plurality of rods terminally fixed to said end walls and disposed longitudinally of said bin, a plurality of resilient arms carried by and depending from said rods, said arms having lower end portions extending below the lower edges of said side walls, and further rods fixed to said end walls, said further rods being disposed intermediate the ends of said arms and contacting the arms, said arms being mounted for vertical swinging movement and said further rods limiting vertical swinging movement of said arms in one direction, each of the troughs having at least one arm associated therewith.

EMANUEL UHRENHOLDT.
